UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

ELECTRICAL IGNITION DEVICE.

Application filed April 21, 1923. Serial No. 633,800.

To all whom it may concern:

Be it known that I, JOHN BERG, a citizen of the United States, residing at Chicago, in the county of Cook and State of Illinois, 5 have invented a new and useful Improvement in Electrical Ignition Devices, of which the following is a specification.

My invention relates, more particularly, to electrical ignition devices of the type generally used in electric cigar-lighters; and my object, generally stated, is to provide improvements in devices of this character to the end that they will function in a highly desirable manner, be simple and of relatively 15 inexpensive construction, and maintained in sufficiently cool condition to permit of the ready handling of the same without danger of burning the operator.

I have illustrated my improvement, as embodied in a device forming one of the elements of an electrical cigar-lighter involving the use of an electric reel and containing features for which I am making separate application for patent. However, I do not 25 wish to be understood as intending to limit my invention to its incorporation in the particular arrangement shown, as it may be used in various other arrangements without departing from the spirit of the invention.

Referring to the accompanying drawings: Figure 1 is a view in side elevation of the electric cigar-lighter referred to, certain parts thereof being shown broken away and in section, the device being shown as secured 35 in an aperture of the instrument board of an automobile. Figure 2 is a broken, enlarged, sectional view of certain of the parts shown in Fig. 1, the electrical ignition device thereof, and to improvements in which my 40 present invention relates, being shown in disassembled, yet related, position to the jack which carries it, the section being taken at the line 2 on Fig. 3 and viewed in the direction of the arrow. Figure 3 is a plan view 45 of the jack of Fig. 2, with the case or shell thereof shown in section. Figure 4 is a longitudinal sectional view of my improved device, the section being taken at the line 4 on Fig. 6 and viewed in the direction of the arrow. Figure 5 is a longitudinal sectional view 50 of the body portion of the device of Fig. 4, with the other parts removed, the section being taken at the line 5 on Fig. 6 and viewed in the direction of the arrow. Figure 55 7 is a longitudinal sectional view of the

center-contact-forming member of the device. Figure 8 is a rear face view of a metal binding member for holding together certain parts of the device. Figure 9 is an edge view of the member of Fig. 8. Figure 10 is 60 a face view of a metal star member forming a part of the structure of Fig. 4. Figure 11 is a face view of a mica star member also forming a part of the structure referred to. Figure 12 is a face view of the electrical 65 heating element employed; and Figure 13, a face view of a perforated mica disk also forming a part of the structure of Fig. 4.

Referring more particularly to Figs. 1, 2 and 3, the structure therein shown comprises 70 a supporting tube 14 which is externally threaded, as represented, and is adapted to be mounted in an opening in an instrument board, as, for example, the opening 15 in the board 16 illustrated and which may be the 75 instrument board of an automobile, the tube 14 being held in place on the board through the medium of nuts 17 and 18 screwed upon this tube and against the back and front faces, respectively, of the board. The tube 80 14, which is open at its opposite ends, connects with the cross-piece 19 of a yoke-shaped clip 20, at the aperture 21 therein, these parts being held together by clamping the cross-piece 19 between deflected annular 85 portions 22 and 23 of the tube 14. Supported in the clip 20 is a housing 24, straddled by the side arms of the clip, to which the housing is secured as by a screw 25 bridging the arms of this bracket, these arms preferably containing inwardly-struck bosses 25* which extend into recesses (not shown) in the side walls of the housing and prevent turning of the housing on the bracket, the 90 housing 24 containing a shaft 26 journaled 95 in the opposite walls thereof and forming a part of an electric reel mechanism shown as of the same general construction as the reel disclosed in United States Patent No. 1,260,626 granted to me March 26, 1918, the 100 wires wound on the reel and located within the housing 24 being represented at 27 and a spring, for automatically re-winding the wire on the reel when drawn therefrom, at 28, the wires 27 extending through an opening 29 in the peripheral wall of the housing 24. The device also comprises a jack represented generally at 30 and formed of a casting 31, preferably of heat-non-conducting 105 material, the end wall of which contains an 110

opening 32 through which the wires 27 extend. The opposite end of the casing 31 contains an electric socket structure 33 comprising an internally-threaded metallic shell 34 and a center contact 34 insulated therefrom by the insulating disk 36. The threaded shell 34 is electrically connected with a contact strip 37 through which the center contact 35 extends and from which it is insulated by the disk 36 and a disk 38 surrounding the center contact, the strip 37 supporting a flexible contact strip 39 secured to the strip 37 by a rivet 40 passing through these elements and insulated therefrom by the tubular, flanged, insulating member 41 and the insulating disk 42, a strip 43 of current-non-conducting material being interposed between the contact strips 37 and 39 and located directly below the strip 39. The strip 37 connects with one of the wires 27 and the strip 39 with the other of said wires, the free end of the strip 39 cooperating with the contact portion 44 of the center contact in engagement with which portion the strip 39 extends except when it is pushed away therefrom against its inherent springiness, as through the medium of the button 44 secured to the strip 39 and movable in an opening 46 in the side wall of the casing 31. The jack 30 is adapted to be inserted into the tube 14 as shown in Fig. 2, in which position the parts are in normal, inoperating, condition, the button 45 being of such size, as shown, that when the jack is introduced into the tube 14 the engagement of the button with the inner surface of the tube 14 causes the contact 39 to be out of engagement with the center contact 35 and thus the circuit through the jack is broken. The jack constructed as described is adapted to have screwed into its socket portion 33 an ignition device 47 embodying my improvements, this ignition device being formed of a main, body, member 48 which, in accordance with one feature of my invention, is formed of any suitable heat-non-conducting material. One face of the member 48 is provided with the stepped recesses 49 and 50 and the other thereof with stepped recesses 51 and 52, all of these recesses being concentrically disposed relative to the axis of the member 48, and the recesses 50 and 51 being separated from each other by an annular web portion 53 forming an integral part of the member 48, this web surrounding a centrally-disposed sleeve portion 54 extending at opposite sides of the web. The end of the member 48 containing the recesses 49 and 50, is recessed at intervals, as represented at 55, these recesses extending through the bottom stepped wall of the recess 49 and into the side wall of this recess. The recesses 55 communicate with slots 56 in the web portion 53 shown as beyond the recess 52, this web portion also containing an opening 57 located within the confines of the recesses 50 and 52. The sleeve-portion 54 contains a passage 58 extending therethrough in which a metallic member 59, forming the center contact of the igniting device, is confined. The member 59 contains, in one end thereof, a socket 60 surrounded by an annular flange 61, and at its opposite end an internally-threaded socket 62 into which a contact screw 63, overlapping the adjacent end of the member 54, is screwed. The other contact member of the ignition device, and which is in the form of a screw plug, is represented at 64, this member, which is adapted to screw into the shell 34 of the jack, surrounding one end of the sleeve 54 and extending at an annular flange portion 65 thereof into the recess 52, the flange portion 65 containing an aperture 66 registering with the aperture 57 in the web 53. The coil of electric resistance wire which forms the heating element of the device, is represented at 67, the terminals 68 and 69 of this coil being electrically connected with the contact plug 64 and the center contact 59 as hereinafter described. The heating element 67 flatwise opposes a perforated disk 70 of mica, backed by a similarly perforated disk 71 of asbestos, these disks surrounding the member 59 at its flanged end, with the flange 61 overlapping the mica disk 70 at the wall of the aperture through the latter. A metal washer 72 extends flatwise against the disk 70, and flatwise opposing this washer at the opposite face thereof is a mica star, represented at 73, which is backed by a metal star 74 of the same shape and size as the mica star 73 with its radiating portions in alignment therewith. The members 70, 71, 72, 73, 74 and 67 are secured together, to form a unitary structure, by a ring 76 having rearwardly-extending lugs 77, this ring fitting flatwise against the outer surface of the member 74, with its lugs 77 extending across the edges of the various members just referred to and bent to overlap the rear face of the disk 71, the structure so provided being seated within the recess 49 and against the mutilated bottom wall 78 of this recess, which latter contains recesses 79 into which the extremities of the lugs 77 extend. The connections between the terminals of the heating element 67 and the contacts of the igniting device are made as follows: The terminal 68 extends through registering apertures in the disks 70 and 71 and into the openings 57 and 66 and is held tightly in place in the opening 66 by a pin 78 driven into these openings and against the terminals 68. The other terminal 69 of the ignition element extends into the socket 60 of the member 59 and is held tightly in engagement therewith by a pin 79' driven into this socket and against the terminal 69.

It will be noted from the foregoing that the ignition device is open from end to end for the circulation of air therethrough, to maintain the parts of the device, at which 5 it is handled by the operator, in cool condition, not only through the openings in the members 70, 71, 72, 73 and 74, the recess 50 and slots 56, but also through the recesses 55 (which extend laterally beyond the ring 76), 10 recess 50 and slots 56; this feature, particularly in connection with that of providing the member 48 of heat-non-conducting material, being especially desirable as it permits of the operator grasping the ignition device. 15 at its heating-element-equipped portion, without danger of burning his fingers.

In connection with the feature just referred to, it may be stated that while the circulation of air through the ignition device 20 produces a cooling effect on the heating element 67, this is not a disadvantage in a cigar-lighter as the cooling effect produced does not impair the device for performing the purpose for which it is provided.

25 While I have illustrated and described a particular construction embodying my invention, I do not wish to be understood as intending to limit it thereto as the same may be variously modified and altered without departing from the spirit of the invention.

30 What I claim as new, and desire to secure by Letters Patent, is:

1. In a device of the character set forth, an insulation body having its front side provided with a chamber, and a resistance element assembly, mounted in said chamber, comprising a spiral of resistance wire, insulation disks at opposite sides of the plane of said spiral, an intervening ring between 40 said disks, and a retainer equipped with means clampingly securing said disks and intervening ring together.

2. In a device of the character set forth, an insulation body provided at its front 45 side with a chamber and at its rear side with a metallic socket member, and a resistance element assembly mounted in said chamber, comprising a pair of insulation disks, an intervening ring, a spiral of resistance wire disposed in the space within said ring, and a retainer equipped with means securing said disks and intervening ring together, said spiral having an eccentric terminal extending through said insulation body and 50 having a central terminal extending through said insulation body and through the socket member thereof.

3. An ignition device comprising an insulation body provided at its front and rear 55 sides with chambers and provided at its rear side with a metallic socket member, a resistance element mounted in the front chamber and having one end eccentrically connected with said socket member, air passages connecting the front and rear cham-

bers, and a central terminal comprising a metallic member extending through said insulation body and the socket-member and attached to the other end of said resistance element and a screw connected with and serving to secure said central metallic member in position, said screw affording a contact surface. 70

4. In an electric igniter, an insulation body equipped with a tubular metallic shank at its rear side affording a terminal and equipped also with a resistance element at its front side, said body having apertures therethrough outside said shank and opening at front and rear sides of said body. 75

5. In an electric igniter, an insulation body equipped with a tubular metallic shank at its rear side affording a terminal and equipped also with a resistance element at its front side, said body having apertures therethrough outside of said shank and opening at front and rear sides of said body and said body having a central portion extending through said metallic shank, and a central terminal extending through the central portion of said body and connected with said resistance element. 85

6. A resistance element assembly comprising a pair of apertured insulation disks, an intervening resistance spiral, a ring clampingly securing said parts together, and a central terminal comprising a metallic member having its front end anchored to one extremity of said spiral and having the other end provided with a threaded bore, and a screw in said bore having a head adapted to serve as a contact. 95

7. A resistance element assembly comprising a pair of apertured insulation disks, an intervening resistance spiral, a ring clampingly securing said parts together, and a central terminal comprising a metallic member having its front end anchored to one extremity of said spiral and having the other end provided with a threaded bore, and a screw in said bore having a head adapted to serve as a contact, in combination with an insulation body having its front face recessed to accommodate said resistance element and having a tubular shank portion through which said central terminal extends, said screw having its head portion provided with a flange which bears against the rear end of the shank portion of the insulation body. 100

8. An ignition device comprising a body-member containing a recess in a face thereof and a passage opening into said recess and opening through the opposite face of said member, and an electrical resistance element located in said recess in spaced relation to the end wall of the latter, said member containing a second passage opening into said recess and opening through the face of said member in which said recess is located. 115 120 125 130

9. An ignition device comprising a body-member containing a recess in a face thereof, and a unitary structure comprising an electrical resistance element and open-work members of insulating material flatwise opposing said element and held together in assembled position located in said recess, said member containing a passage opening into said recess and through the opposite face of said member.
10. An ignition device comprising a body-member containing a recess in a face thereof, and a unitary structure comprising an electrical resistance element and open-work members of insulating material flatwise opposing said element and held together in assembled position located in said recess, said member containing passages opening into said recess and through the opposite faces, respectively, of said member.
11. A cigar-lighting device, comprising a body-member presenting a sleeve-portion at its central portion, an electrical resistance element on said body member, an electrical contact in said sleeve portion and contacting with one of the terminals of said element, and a second electrical contact on said sleeve contacting with the other terminal of said element.
12. A cigar-lighting device, comprising a body-member presenting a sleeve-portion at its central portion, an electrical resistance element on said body-member, an electrical center contact in said sleeve portion and contacting with one of the terminals of said element, and a second screw-plug contact surrounding said sleeve-portion and contacting with the other terminal of said element.
13. An ignition device, comprising a body-member presenting a sleeve-portion at its central portion, an electrical resistance element on said body-member, an electrical center contact in said sleeve portion and contacting with one of the terminals of said element, and a second electrical contact surrounding said sleeve-portion and provided with a flange containing an opening into which the other terminal of said element extends and is secured.
14. An ignition device comprising a body-member containing a stepped recess in a face thereof and presenting a sleeve-portion at its central portion, an electrical resistance element in said recess in spaced relation to the end-wall thereof whereby said member presents a chamber between said element and the end wall of said recess, said member containing passages opening into said chamber and opening through the opposite faces, respectively, of said member to provide air passages, a center contact member in said sleeve portion engaging one of the terminals of said element and a second electrical contact surrounding said sleeve-portion and in engagement with the other terminal of said element.
15. An element of an electrical ignition device, comprising an electrical resistance element, insulating members flatwise opposing said element, and a ring with lugs extending therefrom and having inwardly-extending portions, said elements and members being confined between said ring and the inwardly-extending portions of said lugs.

JOHN BERG.
